UNITED STATES PATENT OFFICE.

EDWARD E. KALLENBACH, OF NEW YORK, N. Y., ASSIGNOR TO THE STANLEY MANUFACTURING COMPANY, OF DAYTON, OHIO, A CORPORATION OF OHIO.

BOTTLE-LABEL PRESS.

1,413,590.

Specification of Letters Patent. Patented Apr. 25, 1922.

Application filed May 19, 1921. Serial No. 471,007.

To all whom it may concern:

Be it known that I, EDWARD E. KALLENBACH, a citizen of the United States, residing in New York, in the county of New York and State of New York, have invented certain new, and useful Improvements in Bottle-Label Presses, of which the following is a specification.

My present invention relates to a machine 10 and process for affixing labels to bottles or like articles.

One object is to provide a machine for affixing by pressure thin flat labels of paper, paper and metal, or any other material to 15 the surfaces of bottles or like articles without kinking or wrinkling of the labels on the surfaces so that the labels will conform to varying configurations of containers.

An additional object is to provide a machine 20 for affixing combined metal and paper labels of the character set forth and described in U. S. Patents 1,018,138; 961,550 and 1,128,071.

Another object is to provide a machine 25 which maintains the label under compression on the bottle, or like article, for sufficient time to allow the glue or adhesive substance on the label to set before removal of the labeled article from the device and without interference with concurrent operations 30 of the device upon similar articles.

An additional object is to provide a machine 35 in which the articles to be labeled are moved away from the operator and returned to the operator after the lapse of a predetermined period during which time the labels which have been applied to the receptacles have been under compression in engagement with the receptacles thus giving 40 the labels time to set and to become permanently affixed to the receptacle before removal from the machine by the operator.

It is my object to provide a machine which 45 will thus enable an operator to be affixing labels to receptacles and inserting them in the machine where they will be kept under compression while the others that have been so treated are moving on the machine back to the operator for removal from the machine. It is my object to provide a continuous operation susceptible of control by 50 a single operator effecting a great saving in time and labor.

It is a further object of the invention to provide a machine which will adapt itself 55 yieldingly to the varying configurations of varying containers and labels. It is my object to provide a machine which will not injure either the containers or the delicate surfaces of the labels themselves. It will 60 be understood that these labels have delicate and expensive colors and lacquers which will be readily injured by improper handling during the period of application of the label to the receptacle. The containers 65 themselves are of delicate character and it is my object to provide a machine which will accommodate itself to the irregularities of such labels and receptacles without injuring them. 70

Another object is to provide a device of the character stated which is simple in construction and efficient in operation.

In the accompanying drawings which show one embodiment of my invention and 75 which form part of this specification, Figure 1 is a top or plan view partly broken away.

Figure 2, is a horizontal detail sectional view. 80

Figure 3, is a detail view on the line 3—3 of Fig. 2, looking in the direction of the arrow.

Similar reference letters or numerals denote similar parts throughout the several 85 views.

My invention comprises in its main parts or elements the base or rest A, the turntable B provided with the lower clamp members, and the pressure arms C provided with 90 the upper clamp members.

The base A, turntable B and arms C may be of wood or suitable metal.

The base A has a plane under surface for resting upon a means, not shown, for supporting the device, or, as may be readily understood, the base A may be provided with legs or other suitable means for resting upon the floor of a building. 95

The base A preferably is circular, and in 100 diameter is less than the diameter of the turntable B, the intention being that the edge of the turntable should extend beyond or overhang the base A to permit ready operation of the device.

The base A has on its upper side the 105

annular extension 10 having in it the annular groove 11 which forms the lower portion of a roller bearing track.

The base A has an upwardly extending lug 12, the base A and lug 12 being apertured for receiving therein the shaft 13 which is fixedly attached to the turntable in a central aperture therein as by the key 14, the shaft 13 being revoluble in the apertures of the lug 12 and base A and the turntable turning with the shaft.

The turntable B has on its under side the annular extension 15 which conforms to the shape of the extension 10 of the base A, and has in it the annular groove 16 which, when the base A and turntable B are in operative relation, overlies the groove 11 and forms the upper portion of the roller bearing track before mentioned for the roller balls 17, located between the base A and turntable B.

The turntable B is provided with a circumferential step or ledge 18, which is cut away at intervals to form the lower clamp members 19, spaced apart radially of the periphery of the turntable and each contoured to receive conformably the rounding portion of a bottle or like article 20 placed longitudinally therein.

30 The turntable B, adjacent to each lower clamp member 19, has an aperture 21 therethrough, which aperture is reduced at its lower end as at 22.

The pressure arms C are arranged radially on the upper surface of the turntable B, so that the upper clamp member of each arm will co-operate with a lower clamp member of the turntable.

Each pressure arm C is a relatively thick strip of wood or metal, preferably of the shape shown in the drawings, wider at its outer end than at its inner end, and loosely attached at its inner end to the turntable B as by the screw 23 passing through the aperture 24 in the arm C, the intention being to permit raising or lifting of the arm C to a position at an angle or incline to the upper surface of the turntable B, as shown in Fig. 2. Each arm C has an aperture 25 therethrough which forms a continuation of the aperture 21 of the turntable B adjacent to a lower clamp member 19 when the arm and lower clamp member are in pressing relation.

55 Each pressure arm C at its outer end in the under side thereof may be inwardly contoured, the contour being arranged for conforming with the rounding portion of a bottle or article. A pad of rubber or other suitable resilient material may be secured to the underside of the arm, the pad forming an upper clamp member 26 for co-operating with the adjacent under clamp member 19. It will be apparent that the 65 rubber pad may be also located upon the

base B, as well as upon the arm C. Or pads may be located on both the arm and the base and I comprehend such an application within the scope of my invention.

A pin 27 is provided for each pressure arm C, the pin 27 having an enlarged portion 28 which is received in the respective apertures 25 and 21 of the pressure arm and turntable. 28 also has a reduced portion 29 which is received in the aperture 22 of the turntable; it passes through the turntable and is fixedly retained in position by a nut 30, which engages the under side of the turntable. By the engagement of the shoulder 31 of the pin with the bottom of the aperture 21 of the turntable the pin 27 provides a guide for the pressure arm C in the raising or lifting movement.

An apertured plate or strip 32 is secured to each arm C across or over the aperture 25 of the arm C, the pin 27 extending through this apertured plate or strip.

A helix spring 33 is arranged around each pin 27, the spring 33 being seated on the bottom of the adjacent aperture 21 of the turntable B and pressing against the adjacent plate or strip 32 of an arm C.

An eccentric or cam member 34 is pivotally attached to the extending end of each pin 27, which eccentric or cam member engages the upper surface of the adjacent plate or strip 32, the eccentric or cam member 34 being provided with an operating arm 35, and provided with a stop 36 for maintaining the eccentric or cam member in vertical 100 position when not operated for camming.

The method of operation is as follows: The operator either stands or sits at some convenient point adjacent to the circumference of the turntable, as at D, Fig. 1, 105 which may be termed the point for insertion and for removal. The clamp members all being in non-clamping or open relation as shown at the left in Fig. 2, the bottle or like article having the metallic label 110 temporarily attached thereto by the glue or adhesive substance which has not yet set, is inserted between the open clamp members so that the label will be engaged by the pad of the upper clamp member. The handle of 115 the eccentric or cam member is pulled down and the bottle or like article is held under pressure between the clamp members as shown at the right in Fig. 2. The device is then revolved to bring the next open pair 120 of clamp members before the operator, and a second bottle or like article with label 125 temporarily thereon is clamped therein. This operation is repeated until all the clamp members are provided with bottles or the like, by which time the first mentioned bottle has made the circuit of the turntable and has arrived in front of the operator, or at the point for removal, the glue or adhesive substance on the label thereof having set 130

during the circuit and the label being securely attached to the bottle. This bottle is then manually released and removed from the clamp members and a bottle or like article to be labeled is substituted therefor in the clamp member, the described operation being repeated until the desired number of bottles or like articles have been labeled.

10 Having thus described my invention it should be understood that there may be modifications thereof and variations therein without departing from the spirit of the invention or exceeding the scope of the appended claims.

When I have referred to receptacles or bottles or the like, I do not desire to confine myself to such receptacles but comprehend within my invention of my machine the application of labels to any type of surfaces whether they be a portion of the container or otherwise. This press enables me to apply labels to flat surfaces as well as to other types of surfaces and to apply the labels to leather, wood, steel or other materials, as well as metal or glass containers.

What I claim and desire to protect by Letters Patent is:—

1. In a bottle press, the combination with a rotatable base having depressions to receive a bottle or other article, of a series of bars loosely connected with said base, one over each depression, each bar having a cushion adapted to impinge the bottle or other article, a stem secured to the base and passing through each bar, a cam lever pivoted to each stem and adapted to depress the bar and press the cushion against the label being applied to the bottle or other article.

2. In a bottle press, the combination with a central shaft, a base in the nature of a table rotatably mounted by means of said shaft and having peripheral depressions, of a series of bars loosely connected with the base, one over each depression, each bar having a cushion, a stem secured to the base and extending through each bar, a spring adapted to elevate each bar, and a cam pivoted to each stem and having a lever by which to operate the cam to depress the bar.

EDWARD E. KALLENBACH.
